FERROMAGNETIC MATERIAL

Gerard Heinrich Jonker, Henricus Petrus Johannes Wijn, and Poul Bernard Braun, all of Eindhoven, Netherlands, assignors, by mesne assignments, to North American Philips Company, Inc., New York, N.Y., a corporation of Delaware

Filed Aug. 9, 1956, Ser. No. 603,136

Claims priority, application Netherlands Aug. 10, 1955

8 Claims. (Cl. 252—62.5)

Our invention relates to oxidic ferromagnetic materials, to methods of preparing these materials and to bodies made from these materials.

Oxidic ferromagnetic materials which exhibit high values of initial permeability are known in the art. All these materials show a decrease of the initial permeability in a certain frequency range the position of which in the frequency scale is related to the low-frequency value of the initial permeability. The initial permeability decreases in a frequency range the position of which in the frequency scale is higher in proportion as the value of the initial permeability at low-frequency is lower. Thus the cores formed from these materials are not too satisfactory for use at high frequencies.

The principal object of our invention, therefore, is to provide a new and novel class of oxidic ferromagnetic materials the initial permeability of which decreases in a much higher positioned frequency range than in the known materials with an equal low frequency value of the initial permeability.

Another object of our invention is to provide oxidic ferromagnetic materials which have initial permeabilities of more and often materially more than 2 at frequencies of about 50 mc./s. and often considerably higher frequencies and which exhibit low losses.

Still another object of our invention is to provide oxidic ferromagnetic materials which may serve as materials for magnetic bodies e.g. cores at frequencies of about 50 mc./s and often considerably higher frequencies.

These and other objects of our invention will be apparent as the specification progresses.

According to our invention we have found new and novel materials having a composition $BaM^{II}Fe_6^{III}O_{11}$ wherein M^{II} is at least one divalent metal selected from the group consisting of Mn, Fe, Co, Ni, Cu, Zn and Mg. In the aforesaid formula Ba may be replaced partly by similar ions, for example Sr, Ca and Pb, since the Ba may be replaced at a maximum for half by Sr or at a maximum for one quarter by Ca or Pb. Of course the Ba-ion, may, as an alternative, be replaced partly by a combination of similar ions. Moreover, the Fe^{III} ions may be replaced for at most one tenth by Cr and/or Al-ions. Thus, the formula for these materials may be restated as follows:

In the formula M^{II} represents one of the aforesaid divalent metals and the subscripts have the following value

- a less than 0.5
- b less than 0.25
- c less than 0.25
- (b+c) less than 0.25
- e less than 0.6
- f less than 0.6
- (e+f) less than 0.6

All these materials have initial permeabilities which do not decrease substantially up to very high frequencies.

2

They have initial permeabilities of more and often materially more than 2 at frequencies of about 50 mc./s. and often considerably higher frequencies. Since they are basically oxidic in nature they are characterized by high ohmic resistances so that eddy current losses are negligibly small. In addition to having greatly improved initial permeabilities at high frequencies, particularly above 50 mc./s., the materials of our invention exhibit relatively low residual loss factors ($\tan \delta$) at frequencies above 50 mc./s.

The novel materials of our invention have a rhombohedral crystal structure of which the unit cell in the hexagonal crystal system has a coaxis of about 43.5 Å and an axis of about 5.9 Å.

While the entire class of our novel materials have improved magnetic properties, particularly in regard to their initial permeabilities, we have found that materials having a composition $BaZn_xMg_yMe^{II}(1-x-y)Fe_6^{III}O_{11}$, where in $0 \leq x \leq 1$, $0 \leq y \leq 1$ and $0 < (x+y) \leq 1$ and wherein Me^{II} is at least one divalent metal selected from the group consisting of Mn, Fe, Co, Ni and Cu, in which formula the Ba may be replaced in the aforesaid manner, have even further improved initial permeabilities.

We prepare the novel materials of our invention by heating at a temperature of more than 1000° C. a finely divided mixture of metallic oxides in a ratio approximately corresponding to that of the metals in the materials of our invention. Alternatively instead of a metallic oxide we may use a material which forms an oxide when heated. As these oxide-forming materials we may use carbonates, oxalates and acetates of the metals. Moreover, instead of metallic oxides we may use one or more preformed reaction products of at least two of the metallic oxides.

Preferably we prepare the novel materials of our invention by heating at a temperature of between 1150° C. and 1300° C. a finely divided mixture of metallic oxides and/or oxide-forming materials and/or reaction products of metallic oxides, in a ratio approximately corresponding to that of the metals in the materials of our invention.

As a preformed reaction product of at least two of the metallic oxides we preferably use an iron-containing reaction product, which has been produced at low temperature, preferably below 1100° C., and which has a crystal structure corresponding with that of the mineral magnetoplumbite, for example $Ba_xSr_{(1-x)}Fe_{12}O_{19}$, where in $0 \leq x \leq 1$.

If necessary the mixture of oxides and/or equivalent materials may be presintered, usually at a relatively low temperature of about 900° C. to 1200° C., the presintered material being reground and resintered several more times if desired before being subjected to the higher temperatures of the process.

In order to facilitate the sintering operation of our process we may include various flux agents, for example silicates such as pentonite or fluorides such as calcium-fluoride in an amount of from 0.25% to 5% in the starting mixtures.

Bodies of desired shape may be formed by sintering the starting mixtures directly in the desired shape. Alternatively bodies of desired shape may be formed by regrinding the sintered material of our invention or the presintered material, molding the resultant powder into the desired shape and sintering the molded product if necessary. A binder such as water, a solution of nitrocellulose or a solution of carboxymethylcellulose may be added to the powdered mixtures before molding if necessary.

In a further embodiment of the invention the finely divided material of our invention is molded to form a

body of the desired shape by pressing the relative material together with a binding agent which is capable of being hardened (for example a polyester resin) or an ethoxylin resin followed by hardening the molded body.

Our invention will now be described in greater detail with reference to the following examples and drawing.

In the drawing, Figs. 1 to 5 are graphs showing the relationship between the values of the real portion of initial permeability, μ' , and the values of the loss factor, $\tan \delta$, to frequency for various embodiments of our invention.

The relationship between the loss factor $\tan \delta$ and the real portion of initial permeability, μ' , will be apparent from the following explanation which forms no part of our invention and which is not to be used in any way to limit the scope of our invention:

The term μ'' as used herein may be explained as follows: A sinusoidally alternating magnetic field with small amplitude will produce a similarly varying inductance in a ferromagnetic body but due to ferromagnetic losses there will be a phase difference between the magnetic field and the inductance. Thus the permeability of the ferromagnetic body, μ , may be represented by a complex magnitude $\mu = \mu' - j\mu''$. The real portion of permeability, μ' , is in phase with the field applied while the other lags in phase by 90° with respect to the applied field. The loss factor "tan δ " can then be defined as

$$\tan \delta = \frac{\mu''}{\mu'}$$

Example I

Mixtures having the following compositions were produced:

- (1) 98.7 gs. of BaCO₃, 245.0 gs. of Fe₂O₃, and 46.3 gs. of MgCO₃,
- (2) 98.7 gs. of BaCO₃, 245.0 gs. of Fe₂O₃, and 64.9 gs. of CoCO₃,
- (3) 98.7 gs. of BaCO₃, 245.0 gs. of Fe₂O₃, and 63.7 gs. of NiCO₃,
- (4) 98.7 gs. of BaCO₃, 245.0 gs. of Fe₂O₃, and 40.8 gs. of ZnO.

Of the raw materials the BaCO₃ was substantially pure, the Fe₂O₃ contained 68.4% by weight of iron, the MgCO₃ 26.2% by weight of magnesium, the CoCO₃ 45.3% by weight of cobalt, the NiCO₃ 46.1% by weight of nickel and the ZnO 78.4% by weight of zinc.

These mixtures were ground for 16 hours with ethyl alcohol in a chromium-plated iron ball mill. The dried powders were then presintered for two hours at 1050° in oxygen. The reaction products were ground for 16 hours. To these dried powders, a small amount of water was then added and rings having an outer diameter of about 35 mms., an inner diameter of about 25 mms. and a height of about 4 mms. were moulded at a pressure of 1000 kgs./cm.². These rings were sintered for two hours in oxygen and then cooled to room temperature within about 4 hours. For the magnesium-, cobalt- and nickel-containing compounds the sintering temperature was 1260° C., and for the zinc-containing compound the sintering temperature was 1240° C. X-ray examination showed that in this manner comparatively pure compounds having desired structure were obtained. Also small quantities of compounds having a spinel crystal structure (probably MgFe₂O₄, CoFe₂O₄, NiFe₂O₄, ZnFe₂O₄) and also a small quantity of BaFe₂O₄ were formed. The properties of this series of compounds are indicated in the table under Nos. 1 to 4.

Example II

A number of rings of the zinc-containing material, described in Example I, were sintered for only half an hour at 1200° C. in oxygen and then cooled to room temperature within about one hour. The properties of these rings are indicated in the table under No. 5.

Example III

A mixture of 26.0 gs. of BaCO₃, 60.0 gs. of Fe₂O₃ and 9.5 gs. of NiO was ground with ethyl alcohol in a porcelain ball mill. The dried mixture was presintered for 15 hours at 1100° C. in air. This reaction product was then ground again for half an hour. From this material rings were molded at a pressure of 1000 kgs./cm.² having an outer diameter of about 35 mms., an inner diameter of 25 mms. and a height of about 4 mms., after the addition of a small quantity of a solution of nitrocellulose as an organic binder. These rings were sintered in oxygen at a temperature of 1290° C. and then cooled to room temperature within about 5 hours. An X-ray examination proved that the material thus obtained consisted almost entirely of the desired compound BaNi^{II}Fe₆^{III}O₁₁, whilst a small quantity of BaFe₂O₄ was formed as a second phase. The properties of the rings are indicated in the table under No. 6.

Example IV

Mixtures having the following compositions were produced:

- (7) 98.7 gs. of BaCO₃, 245.0 gs. of Fe₂O₃, 9.2 gs. of MgCO₃ and 32.6 gs. of ZnO,
- (8) 98.7 gs. of BaCO₃, 245.0 gs. of Fe₂O₃, 13.0 gs. of CoCO₃ and 32.6 gs. of ZnO,
- (9) 98.7 gs. of BaCO₃, 245.0 gs. of Fe₂O₃, 38.2 gs. of NiCO₃ and 16.3 gs. of ZnO.

These mixtures were pre-treated as described in Example I and rings were molded at a pressure of 1000 kgs./cm.² having an outer diameter of about 35 mms., an inner diameter of about 25 mms. and a height of about 4 mms. These rings were heated in oxygen for two hours at 1280° C. and then cooled slowly. An X-ray examination showed that the reaction products formed consisted almost entirely of the desired compounds

40 BaZN_{0.8}Co_{0.2}Fe₆O₁₁, BaZN_{0.6}Ni_{0.4}Fe₆O₁₁, respectively. Also small quantities of compounds having a spinel crystal structure (probably MgFe₂O₄, CoFe₂O₄, NiFe₂O₄, ZnFe₂O₄) were formed. The properties of these compounds are indicated in the table under Nos. 7, 8 and 9.

Example V

A mixture of barium carbonate, strontium carbonate, zinc oxide and ferric oxide in a ratio in accordance with the formula Ba_{0.5}Sr_{0.5}ZnFe₆O₁₁ was ground with ethyl alcohol in a porcelain ball mill. The dried mixture was presintered for 15 hours at 1100° C. in air. This reaction product was then ground again for half an hour. After the addition of a small quantity of a solution of carboxymethylcellulose as an organic binder, rings were molded from this material at a pressure of 1000 kgs./cm.², the rings having an outer diameter of about 35 mms., an inner diameter of about 25 mms. and a height of about 4 mms. These rings were sintered in oxygen at a temperature of 1230° C. and then cooled to room temperature within about 4 hours. By X-ray examination it was found that in this manner a comparatively pure compound of the desired structure was obtained. The properties of the rings are indicated in the table under No. 10.

Example VI

In the manner described in Example V, starting from a mixture of barium carbonate, calcium carbonate, zinc oxide and ferric oxide in a ratio in accordance with the formula Ba_{0.75}Ca_{0.25}ZnFe₆O₁₁, a material was produced which consisted almost entirely of the desired compound, as was proved by X-ray examination, whilst a small quantity of crystals with spinel crystal structure (probably ZnFe₂O₄) was obtained as a second phase. The properties of this compound are indicated in the table under No. 11.

Example VII

In the manner described in Example V, however, with the difference that heating was performed at 1200° C. instead of 1230° C., starting from a mixture of barium carbonate, lead carbonate, zinc oxide and ferric oxide in a ratio in accordance with the formula

a material was produced, which consisted, as was proved by X-ray examination, almost entirely of the desired compound, whilst a small quantity of crystals with spinel crystal structure (probably ZnFe_2O_4) was obtained as a second phase. The properties of this compound are indicated in the table under No. 12.

Example VIII

From BaCO_3 and Fe_2O_3 in the molecular ratio of 1:5.6 by heating the mixture for 15 hours at 900° C. a material was produced which consisted primarily of the compound $\text{BaFe}_{12}\text{O}_{19}$. 33 gs. of this material was mixed with 5.2 gs. of BaCO_3 , 2.26 gs. of ZnO and 21.9 gs. of CoCO_3 , which corresponds to the desired compound

The mixture was ground for one hour with ethyl alcohol in a porcelain ball mill and after drying it was presintered for two hours at 1100° C. in oxygen. After regrinding, the product was shaped in the form of rings at a pressure of 1000 kgs./cm.², which were fired at 1240° C. in oxygen. By X-ray examination it was found that indeed the desired compound was obtained. The properties of the rings are indicated in the table under No. 13.

Example IX

The compounds $\text{BaFe}_{12}\text{O}_{19}$, BaFe_2O_4 and ZnFe_2O_4 were

35 ized.

previously produced by presintering mixtures of correctly chosen proportions of BaCO_3 and Fe_2O_3 , BaCO_3 and Fe_2O_3 and ZnO and Fe_2O_3 at 1150° C. in air. Then a mixture of 15.72 gs. of $\text{BaFe}_{12}\text{O}_{19}$, 20.88 gs. of BaFe_2O_4 and 16.06 gs. of ZnFe_2O_4 , which corresponds to the desired compound $\text{BaZnFe}_8\text{O}_{11}$, was ground for 4 hours with ethyl alcohol in a vibration mill, after which rings were molded from this product at a pressure of 1000 kgs./cm.²; these rings were fired for one hour at 1180° C. in oxygen. X-ray examination proved that in this manner a fairly pure compound with the desired structure was obtained. The properties of the rings are indicated in the table under No. 14.

Example X

From BaCO_3 and Fe_2O_3 in the molecular ratio of 1:5.6 by heating the mixture for 15 hours at 900° C., a material was produced which consisted primarily of the compound $\text{BaFe}_{12}\text{O}_{19}$. 32.4 gs. of this material was mixed with 6.05 gs. of BaCO_3 , 4.9 gs. of ZnO and 1.54 gs. of Al_2O_3 , which corresponds to the desired compound

32.4 gs. of the material was mixed with 6.05 gs. of BaCO_3 , 4.9 gs. of ZnO and 2.33 gs. of Cr_2O_3 , which corresponds to the desired compound $\text{BaZnFe}_{5.5}\text{Cr}_{0.5}\text{O}_{11}$ (16). The mixtures were ground for one hour with ethyl alcohol in a porcelain ball mill and after drying they were presintered for two hours at 1000° C. in oxygen. After regrinding, the reaction products were molded to form rings at a pressure of 1000 kgs./cm.², which were fired at 1250° C. in oxygen. X-ray examination proved that, indeed, the desired compounds were formed. The properties of the rings are indicated in the table under Nos. 15 and 16.

Many other similar compounds may be produced in an analogous manner.

15 In the following table, in column 2, under the heading of "Main Constituent," chemical formulae are indicated, which were derived from the compositions of the starting mixtures and from the X-ray examinations. All measuring results were obtained by carrying out measurements on rings in a demagnetized state at room temperature by the method described by C. M. van der Burgt, M. Gevers and H. P. J. Wijn in "Philips Technical Review," 14, 245 (1952-1953).

The graphs of Figs. 1 to 5 show the relationship between the real portion of the initial permeability, μ' , and $\tan \delta$ to frequency for the products designated in the table under Nos. 1, 2, 4, 5 and 6 respectively. In these graphs the values of μ' and $\tan \delta$ are plotted along the ordinates and the values of the frequencies are plotted along the abscissa. In addition the graph of Fig. 4, which pertains to product No. 5, shows by means of broken lines the properties of the product after it has been magnetized in a strong magnetic field which was subsequently neutralized.

25 30 35

While we have described our invention in connection with specific embodiments and applications, other modifications thereof will be readily apparent to those skilled in this art without departing from the spirit and scope of the invention as defined in the appended claims.

What we claim is:

1. A ferromagnetic material consisting essentially of crystals of a composition having the formula:

in which

M^{II} is at least one divalent metal selected from the group consisting of Mn, Fe, Co, Ni, Cu, Zn, and Mg, and

a has a value less than 0.5

$(b+c)$ has a value less than 0.25

$(e+f)$ has a value less than 0.6

ing of a highly-coherent mass of crystals of a composition having the formula:

in which

M^{II} is at least one divalent metal selected from the group consisting of Mn, Fe, Co, Ni, Cu, Zn, and Mg, and

a has a value less than 0.5

$(b+c)$ has a value less than 0.25

$(e+f)$ has a value less than 0.6

said crystals having a rhombohedral structure, of which the unit cell in the hexagonal crystal can be described with a c -axis of about 43.5 Å. and an a -axis of about 5.9 Å.

3. A permanent magnet comprising a magnetized highly-coherent body consisting essentially of crystals of a composition having the formula:

in which

M^{II} is at least one divalent metal selected from the group consisting of Mn, Fe, Co, Ni, Cu, Zn, and Mg, and

a has a value less than 0.5

$(b+c)$ has a value less than 0.25

$(e+f)$ has a value less than 0.6

said crystals having a rhombohedral structure of which the unit cell in the hexagonal crystal system can be described with a c -axis of about 43.5 Å. and an a -axis of about 5.9 Å.

4. A method of producing a ferromagnetic material which comprises the steps, forming a finely-divided mixture of oxides in proportions forming upon heating crystals of a composition having the formula:

in which

M^{II} is a divalent metal selected from the group consisting of Mn, Fe, Co, Ni, Cu, Zn, and Mg, and

a has a value less than 0.5

$(b+c)$ has a value less than 0.25

$(e+f)$ has a value less than 0.25,

said crystals having a rhombohedral structure, of which the unit cell in the hexagonal system can be described with a c -axis of about 43.5 Å. and an a -axis of about 5.9 Å.; and heating said mixture in an atmosphere containing at least as much oxygen as air at a temperature of about 1000° to 1300° C. for a time sufficient to form said crystals.

5. A method of producing a ferromagnetic material comprising the steps, forming a finely-divided mixture of divalent metal oxides and ferric oxide in proportions yielding upon heating crystals having a structure corresponding to that of the mineral magnetoplumbite; heating said mixture at a temperature below 1100° C. and sufficiently high to form said crystals; mixing said crystals with additional oxides of divalent metals in amounts sufficient to form upon heating crystals of a composition having the formula:

in which

M^{II} is a divalent metal selected from the group consisting of Mn, Fe, Co, Ni, Cu, Zn, and Mg, and

a has a value less than 0.5

$(b+c)$ has a value less than 0.25

$(e+f)$ has a value less than 0.6,

said latter crystals having a rhombohedral structure, of which the unit cell in the hexagonal system can be described with a c -axis of about 43.5 Å. and an a -axis of about 5.9 Å.; and heating the latter mixture in an atmosphere containing at least as much oxygen as air to a tem-

perature of about 1000° to 1300° C. for a time sufficient to form said latter crystals.

6. A method of producing a ferromagnetic material comprising the steps, forming a finely-divided mixture of divalent metal oxides in proportions forming upon subsequent heating crystals of a composition having the formula:

10 in which

M^{II} is a divalent metal selected from the group consisting of Mn, Fe, Co, Ni, Cu, Zn, and Mg, and

a has a value less than 0.5

$(b+c)$ has a value less than 0.25

$(e+f)$ has a value less than 0.6,

said crystals having a rhombohedral structure, of which the unit cell can be described with a c -axis of about 43.5 Å. and an a -axis of about 5.9 Å.; heating said mixture to a temperature between about 900° to 1200° C. to react the same; finely-dividing the reaction product; and heating the finely-divided reacted product in an atmosphere containing at least as much oxygen as air to a temperature of about 1000° to 1300° C. for a time sufficient to form said crystals.

7. A method of producing a ferromagnetic body which comprises the steps forming a finely-divided mixture of oxides in proportions forming upon heating crystals of a composition having the formula:

in which

M^{II} is a divalent metal selected from the group consisting of Mn, Fe, Co, Ni, Cu, Zn, and Mg, and

a has a value less than 0.5

$(b+c)$ has a value less than 0.25

$(e+f)$ has a value less than 0.25,

said crystals having a rhombohedral structure, of which the unit cell in the hexagonal system can be described with a c -axis of about 43.5 Å. and an a -axis of about 5.9 Å.; compacting said mixture into a body of desired shape and dimensions; and heating said compacted body in an atmosphere containing at least as much oxygen as air at a temperature of about 1000° to 1300° C. for a time sufficient to form said crystals.

8. A method of producing a permanent magnet body which comprises the steps forming a finely-divided mixture of oxides in proportions forming upon heating crystals of a composition having the formula:

in which

M^{II} is a divalent metal selected from the group consisting of Mn, Fe, Co, Ni, Cu, Zn, and Mg, and

a has a value less than 0.5

$(b+c)$ has a value less than 0.25

$(e+f)$ has a value less than 0.25,

said crystals having a rhombohedral structure, of which the unit cell in the hexagonal system can be described with a c -axis of about 43.5 Å. and an a -axis of about 5.9 Å.; compacting said mixture into a body of desired shapes and dimensions; heating said compacted body in an atmosphere containing at least as much oxygen as air at a temperature of about 1000° to 1300° C. for a time sufficient to form said crystals; and magnetizing said body in a strong magnetic field.

UNITED STATES PATENT OFFICE
CERTIFICATE OF CORRECTION

Patent No. 2,946,753

July 26, 1960

Gerard Heinrich Jonker et al.

It is hereby certified that error appears in the printed specification of the above numbered patent requiring correction and that the said Letters Patent should read as corrected below.

Column 2, line 13, for "coaxis" read -- c-axis --; line 14, for "an axis" read -- an a-axis --; line 57, for "pentonite" read -- bentonite --; column 7, line 16, and column 8, line 47, for "permanent magnet", each occurrence, read -- ferromagnetic body --.

Signed and sealed this 10th day of January 1961.
